UNITED STATES PATENT OFFICE.

CLAYTON HOUGH, OF ATCO, NEW JERSEY.

SPARK PLUG.

1,413,478.

Specification of Letters Patent. Patented Apr. 18, 1922.

Application filed February 27, 1920. Serial No. 361,619.

To all whom it may concern:

Be it known that I, CLAYTON HOUGH, a citizen of the United States, residing at Atco, in the county of Camden and State of New Jersey, have invented new and useful Improvements in Spark Plugs, of which the following is a specification.

My invention relates to a new and useful improvement in spark plugs, and has for its object to so construct such a plug as to provide for the accurate adjustment of the spark gap.

With this end in view, this invention consists in the details of construction and combination of elements hereinafter set forth and then specifically designated by the claim.

In order that those skilled in the art to which this invention appertains, may understand how to make and use the same, I will describe its construction in detail, referring by numerals to the accompanying drawing forming a part of this application, in which:—

Fig. 1, is a side elevation of a plug having my improvement embodied therein, a portion being broken away and sectioned so as to clearly show the construction of the adjusting mechanism.

Fig. 2, is an end view of Fig. 1 looking upward.

Fig. 3, is an enlarged view of the lower portion of Fig. 1.

Fig. 4, is a bottom plan view of a slightly modified form of the adjustable member.

Fig. 5, is a central section of Fig. 4, and

Fig. 6, is a side elevation of Fig. 4.

In carrying out my invention as here embodied, 1 represents a spark plug of usual construction having the threaded shank 2 for securing in the head of a cylinder of an internal combustion engine, the lower end of this shank is reduced in diameter to form the hub 3 which is externally threaded.

4 represents a collar which is internally threaded adapted to be secured on to the threaded hub 3, and this collar is provided with a bridge wire 5 which forms the extremity of the spark gap on the ground side

of the circuit. 6 is a lock nut also threaded upon the hub 3 adapted to be jammed against the upper face of the collar 4 when the latter has been properly adjusted, thus holding this collar against accidental displacement.

7 represents the stem, the lower end of

which forms the spark gap extremity of the positive side of the circuit, and across the lower end of this stem extends the bridge wire 5 so that when the collar 4 is screwed up or down upon the hub 3 this bridge wire 60 will be brought closer to or removed further from the lower end of the stem, thus lessening or increasing the spark gap as described, and when the proper adjustment of the spark gap has been thus secured the jam 65 nut 6 is firmly set against the collar so as to maintain this adjustment.

Heretofore the adjustment of the spark gap wires has been effected by bending the same back and forth which seldom produced 70 satisfactory results and loosen the wires in their fastenings, but by my improvement these disadvantages are entirely overcome as the bridge wire is adjusted bodily to and from the lower end of the stem with great 75 accuracy on account of running the collar which carries said wire upon the threaded hub.

Should it be found desirable the side walls of the collar 4 may be extended downward 80 sufficiently to permit a horizontal wire to be inserted between the same and secured therein, but for most purposes I prefer that the adjustable member may be made entirely in one piece so as to prevent the loosening of 85 the wires therein on account of the change of temperature when the plug is in use, and I have shown such a construction in Figs. 4, 5 and 6. In this last named construction the adjusting member consists of the body 3 90 having formed therewith the bridge 9 the body being internally threaded as indicated at 10. This form of adjusting member is cheap to manufacture since the body may be drawn up in the form of a shallow shell and 95 the bridge produced by milling away a portion of the sides of said shell leaving the bridge.

Of course I do not wish to be limited to the exact details of construction as herein 100 shown as these may be varied within the limits of the appended claim without departing from the spirit of my invention.

Having thus fully described my invention, what I claim as new and useful is:—

In combination, a spark plug including 105 the ordinary threaded shank and having a stem or electrode projecting therefrom, an externally threaded hub formed with said spark plug of less diameter than the shank, 110

a collar on said hub and normally located above the outer end of the electrode or stem, a lock nut mounted on the hub above the collar for holding the latter in any adjusted 5 position, a bridge forming an electrode carried by said collar and having a portion underlying the stem of the spark plug so as to

be adjustable relative thereto when the collar carrying the same is adjusted upon its hub.

10

In testimony whereof, I have hereunto affixed my signature.

CLAYTON HOUGH.
